FIG. 1 is a front perspective view of a combination flashlight and stun gun, showing a first embodiment of our new design; FIG. 2 is a rear perspective view of FIG. 1; FIG. 3 is a front elevational view of FIG. 1; FIG. 4 is a rear elevational view of FIG. 1; FIG. 5 is a right-side elevational view of FIG. 1; FIG. 6 is a left-side elevational view of FIG. 1; FIG. 7 is a top plan view of FIG. 1; FIG. 8 is a bottom plan view of FIG. 1; FIG. 9 is a front perspective view of a second thereof; FIG. 10 is a front elevational view of FIG. 9; FIG. 11 is a left-side elevational view of FIG. 9; FIG. 12 is a right-side elevational view of FIG. 9; FIG. 13 is a top plan view of FIG. 9; and FIG. 14 is a bottom plan view of FIG. 9.

FIG. 15 is a front perspective view of a third embodiment thereof;

FIG. 16 is a front elevational view of FIG. 15;

FIG. 17 is a left-side elevational view of FIG. 15;

FIG. 18 is a right-side elevational view of FIG. 15;

FIG. 19 is a top plan view of FIG. 15; and,

FIG. 20 is a bottom plan view of FIG. 15.

The broken lines in the drawings depict matter that forms no part of the claimed design. It is understood that the rear elevational views of all embodiments are identical.
